UNITED STATES PATENT OFFICE.

JAMES JONES, OF BROOKLYN, NEW YORK, ASSIGNOR TO C. D. JONES,
OF SAME PLACE.

DESIGN FOR A PENCIL-CASE.

SPECIFICATION forming part of Design No. 18,491, dated July 31, 1888.

Application filed June 14, 1888. Serial No. 277,148. Term of patent 3½ years.

To all whom it may concern:

Be it known that I, JAMES JONES, a subject of the Queen of Great Britain, and a resident of Brooklyn, in the county of Kings and State 5 of New York, have invented a certain new and original Design for Lead-Pencil Cases, of which the following is a specification.

Of the drawings, Figure 1 is a perspective view of my design. Fig. 2 is a side view, and Fig. 3 is an end view of the same.

My design consists of a straight cylindrical barrel, A, having at one end a broad flat head, B, near which are two or more rows of indentations, D, in the barrel. The other end terminates in a square tapering point, C, the planes

of which intersect the cylindrical barrel in semi-ellipses, as shown.

I claim—

The design for lead-pencil cases, consisting of the barrel A, having the indentations D, the flat head B, and square point C, as herein shown and described.

Signed at Brooklyn, in the county of Kings and State of New York, this 5th day of June, A. D. 1888.

JAMES JONES.
